UNITED STATES PATENT OFFICE.

LEONARD E. SHANE, OF KEYTESVILLE, MISSOURI.

DESIGN FOR A WRECKING-BAR WITH HAMMER ATTACHMENT.

45,821.

Specification for Design.

Patented May 19, 1914.

Application filed February 17, 1914. Serial No. 819,289. Term of patent 14 years.

To all whom it may concern:

Be it known that I, LEONARD E. SHANE, a citizen of the United States, residing at Keytesville, county of Chariton, and State of Missouri, have invented a new, original, and ornamental Design for a Wrecking-Bar with Hammer Attachment, of which the following is a specification, reference being had to the accompanying drawing, forming part thereof.

The figure is a perspective view.

I claim:

The ornamental design for a wrecking bar with hammer attachment, as shown.

LEONARD E. SHANE.

Witnesses:

A. F. TAYLOR,
O. P. RAY.
